United States Patent Office.

B. B. HOTCHKISS. OF NEW YORK, N. Y.

Letters Patent No. 93,089, dated July 27, 1869; antedated July 20, 1869.

IMPROVEMENT IN PROJECTILES FOR ORDNANCE.

The Schedule referred to in these Letters Patent and making part of the same.

To all whom it may concern:

Be it known that I, B. B. HOTCHKISS, of the city and county of New York, and State of New York, have invented certain new and useful Improvements in Projectiles for Rifle-Cannon; and I do hereby declare that the following is a full and exact description thereof.

My invention relates to the form of the cast-iron part, or hard body, and to the form of the brass or soft packing-material, and to the relations of these parts to each other, and to the rifle-grooves in the gun.

It is an improvement based on the expanding-button projectile, described in an application for patent, filed by me, on or about May 28, 1868.

I will first describe what I consider the best means for carrying out my invention, and will afterward designate the points which I believe to be new therein.

The accompanying drawings form a part of this specification.

Figure 1 is a side view of my projectile before being fired.

Figure 2 is a rear view of the same.

Figure 3 is a central longitudinal section, and

Figure 4 is a cross-section on the line S S, in figs. 1 and 3.

Figure 5 is a corresponding longitudinal section, showing the relation of the parts after the projectile has been fired, and

Figure 6 is a corresponding cross-section.

In order to show, as closely as possible, the points of difference between this and my former projectile, I have also presented two figures, showing the projectile in the two conditions, cut on a different plane, as follows:

Figure 3^a represents a longitudinal section on the line T T, before the firing, and

Figure 5^a represents a longitudinal section on the line T T, after the firing.

Neither the projectile described in my former application, nor any other expanding-button projectile known to me, has had grooves on the body for the buttons, allowing the buttons to move forward therein.

I provide such, making them to decrease in depth forward, and I support the buttons directly, on each side, up to the full cylindrical surface of the projectile.

There are additional features of the invention, and additional figures, which will be fully described below.

Similar letters of reference indicate corresponding parts in all the figures.

A is the body of the projectile;

A' is a central projection, formed on the rear, to aid in retaining the packing-piece; and

a a a are wedge-shaped cavities, or inclined grooves, formed in the periphery of the body A, near the rear.

The form of these grooves, and of that portion of the brass which fits therein, is very important. The depth of the grooves decreases gradually from the rear for-

ward. The width is correspondingly contracted, but to a less extent.

The number of these wedge-shaped grooves should correspond with the number of grooves in the gun for which the projectile is adapted.

The packing-piece B B' B' is cast separately in the form represented, and is sufficiently soft to be changed, as represented in figs. 3^a and 5^a, in the act of being discharged from the gun.

There is an annular cavity, b, under the rear part B of the packing-piece.

The act of firing drives the packing-piece B forward, and tends to increase its radial dimensions, by flattening it against the rear of the body A, but this tendency is of little value. I attach importance mainly to its functions in relation to other parts.

The parts B' B', which I term expanding-buttons, may be cast with the part B, and form a portion of a single casting. They are arranged around the rim of the part B, and correspond in number and in form with the wedge-shaped grooves a, in the body A, but are a little narrower.

They are adapted to fit in these grooves a, as represented, standing in the rear portions of said grooves when the projectile is placed in the gun, with liberty to move forward, and to be thereby wedged outward when the gun is fired.

The width of each button, B', should be no greater than the width of the wedge-shaped grooves a, in which they are to move forward, so that they may be driven forward easily, and be extended thereby.

These parts B' are so made as to project out beyond the cylindrical surface of the body A, like what are known as buttons, or *boutons* on the well-known French projectiles, but they should not, before using, project out so far as to bear hard on the bottom of the several grooves in the gun.

The intense force produced by the ignition of the powder, in the act of firing, drives forward the buttons B', in the grooves a, and expands them radially, so as to cause them to bear firmly on the bottoms of their respective grooves in the gun.

In giving the rifle-motion to the projectile, the several expanding-buttons B' are pressed to one side, in their respective grooves a. Each is supported and enabled to resist "wringing," by its direct and fair contact against the side of its groove a. In other words, the cylindrical portions of the cast-iron, marked a', which stand between the several grooves a, offer a support, direct and firm, to resist any movement of the buttons B', after they have each moved to one side sufficiently to press against one side of their respective grooves.

The slight taper given to the width of the buttons B' corresponds with the twist of the grooves in the gun in which the projectile is intended to be used.

Guns are sometimes made with a right-hand twist, and sometimes with a left-hand twist. By inclining both edges of each part, or buttons, B' I adapt my projectile equally well for each style of groove, presenting a surface just sufficiently inclined to bear fairly against the side of each kind of groove. I have adapted the projectile here represented for a twist of once in eleven feet.

When fired from a gun rifled with the right-hand twist, the buttons B' are pressed each to one side of their respective grooves *a*, and when fired from a gun rifled with a left-hand twist, the buttons are pressed against the other side of their respective grooves. In either case, they are directly and firmly supported.

My casting A may be extended backward between the grooves *a*, if preferred, and additional buttons, made either expansible or non-expansible, may be produced on the body A of the projectile, or may be fixed there by any approved means, and used in combination with my peculiar packing-arrangements, if preferred.

I have in a former application for patent, described legs or rearward extensions of the casting A, such as I would employ with this invention, as above suggested. The novelty in my present invention relates to the parts in front of said legs, and in rear of the ordinary French *boutons*, if such are used.

I will now speak of the cavity, or groove *a'*, and its functions. When the parts B' are driven forward, they are compressed or wedged with great force in the grooves *a*, and the brass is sufficiently plastic to change its form, wherever allowed under such circumstances.

The cavity *a'* allows portions of the brass to be received therein, and thus to aid in locking itself upon the body A.

Figures 7 and 8 are sections, showing this part of the projectile on a larger scale, fig. 7 showing the relation of the parts before the firing, and fig. 8 showing the same after the firing.

By making the cavity *a'* in the form of a deep groove, extending quite around the body A, as represented, I facilitate its production by aid of a lathe, and also provide for the locking of the brass, by extension laterally on each side of the wedge-shaped grooves *a*, as well as its bending or gushing inward.

The length of the parts B' may vary. They may be short, as indicated in fig. 1, so as to not reach the cross-groove *a'* until after the firing has driven them forward, or they may be longer, and extend forward further, as indicated in the other figures.

I prefer the latter construction; that is, to make the points of the wedges reach forward into the cross-groove *a'* before the firing, and to be doubled up and upset there very greatly by the act of firing.

In such construction, I propose to bend the points of the parts B' inward, by hand or by machinery, and thus cause them to lock slightly in the groove *a'*, when the projectile is made.

It will be observed that all of the features of the invention to which attention has been particularly called until now, can be carried out by the use of pieces B', cast and attached each separately from the others. I greatly prefer, however, to attach all the parts B together, or, in other words, form them all in a single casting, as shown in fig. 2, and to secure the whole, by riveting, at a single point, in the centre of the rear of the projectile.

I do not claim any of the several features, except in expanding-button projectiles; that is to say, in combination with means for expanding the packing in and adjacent to the rifle-grooves, and allowing windage between the projectile and the lands of the gun, as specified; but,

Having now fully described my invention,

What I claim as new, and desire to secure by Letters Patent, is as follows:

1. So constructing the expanding-buttons B', and so mounting them in the wedge-shaped cavities *b*, supported by the ridges *a'*, as represented, that the buttons shall expand strongly, but slightly, by moving forward to a definitely-limited extent in the act of firing, substantially as and for the purposes herein set forth.

2. I claim the cavity *b*, under the packing at the rear, in combination with the wedging-grooves *a*, full cylindrical surfaces *a'*, and buttons B', adapted to move forward, and be expanded by such motion, all as and for the purposes herein set forth.

3. I claim the provision *a'*, in combination with grooves *a* and expanding-buttons B, for receiving and locking portions of the said buttons B' as herein specified.

4. I claim a projectile, having a packing formed in a single piece, and having the following several qualities in combination: first, an expanding-plate, or disk, B, adapted to receive the force of the discharge over the whole rear of the projectile; second, a central locking, or fastening thereof; and, third, the segmental wedges, or buttons B', directly supported against wringing by the projections *a*, on the exterior of the body A, all constructed, combined, and arranged as and for the purposes herein set forth.

In testimony whereof, I have hereunto set my name, in presence of two subscribing witnesses.

B. B. HOTCHKISS.
